(57) **CLAIM**

The ornamental design for a water toy, as shown and described.

DESCRIPTION

FIG. 1 is an isometric view of a water toy showing my new design;

FIG. 2 is a left side view thereof;

FIG. 3 is a front view thereof;

FIG. 4 is a right side view thereof;

FIG. 5 is a top view thereof;

FIG. 6 is a bottom view thereof; and,

FIG. 7 is an alternate orientation view thereof.

The broken lines are for illustrative purposes only and form no part of the claimed design.
